DESIGN FOR A FOOT EXERCISER

William M. Jeffreys, Youngstown, Ohio

Application February 22, 1943, Serial No. 109,605

Term of patent 3½ years

To all whom it may concern:

Be it known that I, William M. Jeffreys, a citizen of the United States, residing at R. F. D. #2, Hopkins Road, Youngstown, in the county of Mahoning and State of Ohio, have invented a new, original, and ornamental Design for a Foot Exerciser, of which the following is a specification, reference being had to the accompanying drawing, forming part thereof.

Figure 1 is a perspective view of a foot exerciser, showing my new design; and Figure 2 is a longitudinal sectional view taken substantially on line II—II of Figure 1.

I claim:

The ornamental design for a foot exerciser, as shown.

WILLIAM M. JEFFREYS.
